UNITED STATES PATENT OFFICE.

JOHN HENRY MAWBY, OF WEST MIDLAND, WESTERN AUSTRALIA, AUSTRALIA.

PNEUMATICALLY DRIVEN SHIP.

Application filed January 15, 1927, Serial No. 161,386, and in Australia October 25, 1926.

This invention provides means for driving a ship or other water borne vessel by the action of compressed air which is introduced through nozzles into an open ended tubular keel of the ship. According to the invention one or more tubular keels are secured to the hull of said ship and extend for a partial or full length thereof. These keels are open at both ends and have bell-shaped mouths in order to facilitate the inflow and outflow of the water and at each end are fitted with hinged apertured doors to prevent the entry of sea weed or other objectionable matter. Within these keels are fitted one or 15 more nozzles which are connected by valve controlled pipes with an air compressor installed in the ship. These tubular keels have lateral openings in each of which is fitted a blade secured on a vertical shaft 20 which extends upwardly into the ship and is operated either by manual or motive power. The function of said blades is to outwardly and laterally divert the water in order to steer the ship in either direction and thus dispense with existing types of steering gear. In order that my invention may be clearly understood the same will be explained with the aid of the attached drawings wherein

Fig. 1 is a side elevation of a ship fitted 30 with my invention.

Fig. 2 is an end view of same. Fig. 3 is an enlarged longitudinal broken sectional elevation of a tubular keel with its nozzles and diverter blades.

Fig. 4 is a broken sectional plan view on line 4—4 of Fig. 3 one of the diverter blades being shown in dotted lines in its diverting position.

Fig. 5 is a sectional end view on line 5—5 of Fig. 3. Referring to said drawings:—

At an approved position or positions on the hull 8 of the ship are secured a plurality of tubes 9 arranged in central longitudinal alignment with each other, as seen in Fig.

45 1. Said tubes are open ended and bell mouthed as at 10 and each mouth is fitted with an apertured hinged door 11 to prevent entry of objectionable matter. Within each of said tubes are positioned oppositely directed nozzles 12. Since the tubes are of the same construction, it will be sufficient to describe only one of them and the instrumentalities associated therewith.

The nozzles 12 are in communication by 55 means of valve controlled pipes 13 with an air compressor 14 installed in the hull 8.

Each tube has a pair of opposed lateral openings 15 and within each of said openings is fitted a blade 16 keyed on a vertical shaft 17 extending upwardly into the hull 8 and operated either by manual or motive power. This shaft 17 is held in footstep and guide bearings 18 and 19 respectively. In order to move the ship laterally, one or more transverse tubes 20 are fitted within the hull 8, said tubes being open ended and bell mouthed as at 21 and fitted with apertured doors 22 for the purpose above mentioned. The tubes 20 are fitted with nozzles 23 communicating by valve controlled pipes 24 with air compressor 14.

The pipes 13 and 24 lead from the bottom of the air compressor 14 whereby any water which may gain access to the compressor may flow with the air and be ejected through the nozzles, thus effecting an initial impulse to the suctional action of latter. I do not limit myself to the number positioned or length of the tubular keels and transverse tubes employed, nor do I restrict myself to the number or position of the nozzles or diverter blades which may be used. The operation of the invention is as follows:—

When air is fed from the compressor 14 through the pipes 13 and nozzles 12 into the tubular keels as 9, the outrush of air causes a suctional action to be set up within said keels and a corresponding sudden rush of water thereto which passes out at the discharge ends of said keels, resulting in the propulsion of the ship in an opposite direction to that in which the nozzles are directed, the direction in which the ship is propelled being determined by the position of the nozzles which are employed. For steering

the ship one or both of the diverter blades 16 on the shafts 17 are given the needful unit of rotation to a position such as shown by dotted lines in Fig. 4, thus diverting portion of the water through its respective opening 15, which action results in a divergence of travel of the ship from that of a straight course. When it is desired to move the ship in a lateral direction air is fed from compressor 14 through nozzles 23 into the transverse tubes 20 thus resulting in a like action as that before described in connection with the longitudinal keels.

What I claim as my invention and desire to secure by Letters Patent is:—

1. The combination with a hull and a fluid compressor therein, of a propelling and

steering device for the hull comprising an open tube flared at both ends, a grate fitted across each end of said tube, oppositely directed nozzles mounted centrally of the tube, 5 said nozzles being in communication with the compressor, and steering means mounted in the walls of said tube and in the path of the fluid projected from one of the nozzles.

2. The combination with a hull and a fluid 10 compressor therein, of a propelling and steering device for the hull comprising an open tube flared at both ends and having opposed lateral openings, a grate fitted

across each end of said tube, oppositely directed nozzles mounted centrally of the tube, 15 said nozzles being in communication with the compressor, and two blades pivoted, respectively, in the lateral openings of the tube and mounted so as to be projected within the tube to deflect the flow of fluid from one of the nozzles and acting as a steering means 20 for the hull.

In testimony whereof I have hereunto set my hand.

JOHN HENRY MAWBY.
